DESIGN FOR A KEY RING

Karl Fassnacht, Cranston, R. I., assignor to
Speidel Corporation, Providence, R. I., a corpo-
ration of Rhode Island

Application April 15, 1940, Serial No. 91,681

Term of patent 14 years

To all whom it may concern:

Be it known that I, Karl Fassnacht, a citizen
of the United States, residing at Cranston, in the
county of Providence and State of Rhode Island,
have invented a new, original, and ornamental
Design for a Key Ring, of which the following
is a specification, reference being had to the ac-
companying drawing, forming part thereof.

Fig. 1 is a front elevational view of the key
ring showing my new design.

Fig. 2 is a rear elevational view of the same,
and,

Fig. 3 is a side elevational view of the key
ring, as seen looking from the right of Fig. 1.

I claim:

The ornamental design for a key ring, sub-
stantially as shown.

KARL FASSNACHT.
